UNITED STATES PATENT OFFICE.

LESLIE I. McDEVITT, OF HOUSTON, TEXAS.

COMBINATION SWING AND COUCH.

1,330,204.

Specification of Letters Patent. Patented Feb. 10, 1920.

Application filed August 19, 1919. Serial No. 318,596.

To all whom it may concern:

Be it known that I, LESLIE I. McDEVITT, a citizen of the United States, residing at Houston, in the county of Harris and State 5 of Texas, have invented certain new and useful Improvements in Combination Swings and Couches, of which the following is a specification.

This invention relates to new and useful 10 improvements in a combination swing and couch.

One object of the invention is to provide a device of the character described, specially designed for the use of infants and small 15 children and comprehending a swinging seat which is readily convertible into a swinging couch.

Another object of the invention is to provide a device of the character described 20 which may be easily collapsed and folded together, so as to occupy small space when not in use.

A further feature of the invention is to provide a device of the character described, 25 which is simple in construction and consequently may be cheaply and easily manufactured.

With the above and other objects in view, the invention has particular relation to certain 30 novel features of construction, arrangement of parts and use, an example of which is given in this specification and illustrated in the accompanying drawings, wherein—

35 Figure 1, shows a front elevation of the device.

Fig. 2, shows a side elevation thereof.

Fig. 3, shows a fragmentary perspective view, shown as a swinging seat.

40 Fig. 4, shows a fragmentary perspective view shown as a swinging couch, and

Fig. 5, shows a side view of the adjusting link employed.

Referring now more particularly to the 45 drawings, wherein like numerals of reference designate similar parts in each of the figures, the numerals 1, 1, and 2, 2, respectively, refer to the front and rear legs which are spaced apart and connected together at 50 their upper ends by means of the cross bars 3 and 4, thus forming the supporting framework, said legs 1 and 2, at each side being pivoted together at the point 5. A body, consisting of the bottom 6 and the upstanding fixed sides 7, 7, is suspended between

said legs by means of the front and rear suspending chains or cords 8, 8, and 9, 9, which are attached at their upper ends to the respective bars 3 and 4, and at their lower ends to the corresponding sides 7, 7. 60 A foot rest is provided consisting of the sections 10, and 11, which are hinged together and the former of which is hinged to the front end of the bottom 6. Links 12 are pivotally connected, at one end, to 65 each end of the section 11 and the other ends of these links are formed with hooks 13, adapted to engage over the studs 14, projecting out from the respective ends of the sections 10, so as to hold said sections 70 10 and 11 in position as a foot rest when the device is used as a swinging seat, as illustrated in Fig. 3. When the device is used as a swing couch, the hooks 13 may be engaged over the studs 15 carried by the 75 front ends of the sides 7, to hold said sections 10 and 11 in position to form a closed end of the body, as illustrated in Fig. 4. A table board 16 is arranged at the front end 80 of the body, whose ends rest upon the sides 7. One of the chains 8 passes through an opening in one end of this board and the other end of the board has an end notch 17, through which the other chain 8 passes, thus permitting the last mentioned end to be disengaged, and the board 16 to be swung around out of the way as shown in Fig. 3.

85 A reclining back 18 is provided which is hinged at its lower end to the back end of the bottom 6, and hinged to each edge of this 90 back are the side guards 19, 19, which may be folded down on the back when desired. When in use, these guards will stand at right angles to the back, and when used, as a couch, the back 18 will form a continuation 95 of the bottom 6, and will be held in that position by means of side links 12', 12', similar to the link 12, said side links being pivoted at one end to the rear ends of the sides 7, and at their other end, being formed 100 into hooks which engage over studs 20 projecting inwardly from the adjacent ends of the guards 19. The back is also sustained in reclining position by side cords, or chains 21, 21, which are attached at their upper ends 105 to the cross bar 4, and at their lower ends to the free end of said back. When the device is used as a seat or swing, the back is brought into approximately vertical position and there held by engaging the hooks 110

of the links 12', 12'', over corresponding studs as 22, projecting out from the edges of the back 18.

The entire device is mounted on wheels 5 23, so as to be readily movable and as is obvious, may be easily collapsed and folded up when not in use.

What I claim is:

- 10 1. A device of the character described, including a body having a bottom and sides, a foot rest hinged to the front end of the bottom and including two sections hinged together, means for securing said sections in a fixed position relative to each other and to said bottom, a back hinged to the rear end of said bottom, side guards hinged to the side edges of said back and means for holding said back at different points of adjustment relative to the bottom.
- 20 2. A device of the character described, including a body, having a bottom and sides, means for suspending said body, a foot rest hinged to the front end, of the bottom and including two sections hinged together, 25 means for securing said sections in a fixed position relative to each other, and to said bottom, a back hinged to the rear end of said bottom, side guards hinged to the side edges of said back and means for holding 30 said back at different points of adjustment relative to the bottom.

3. A device of the character described in-

cluding a supporting framework, a body suspended therefrom and including a bottom and sides fixed thereto, a foot rest hinged 35 to the front end of the bottom and including two sections hinged together, means for securing said sections in a fixed position relative to each other, and to said bottom, a back hinged to the rear end of said bottom, guards 40 hinged to the side edges of said back and means for holding said back at different points of adjustment relative to the bottom.

4. In a device of the character described, a body formed of a bottom and sides, a foot 45 rest hinged to the front end of the bottom and formed of two sections hinged together, means for holding said sections in a given position relative to each other, said means being also adapted to hold said foot rest in 50 a given position relative to said body, a back hinged to the rear end of the bottom, means for holding said back in a given position relative to the body, and side guards 55 hinged to the side edges of the back and adapted to stand at right angles thereto or to be folded down thereon.

In testimony whereof I have signed my name to this specification in the presence of two subscribing witnesses.

LESLIE I. McDEVITT.
